ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

WARP-TENSION-LOCKING MECHANISM FOR LOOMS.

1,427,636.

Specification of Letters Patent. Patented Aug. 29, 1922.

Application filed January 3, 1921. Serial No. 434,753.

To all whom it may concern:

Be it known that I, ALONZO E. RHOADES, a citizen of the United States, and resident of Hopedale, county of Worcester, State of Massachusetts, have invented an Improvement in Warp-Tension-Locking Mechanisms for Looms, of which the following description, in connection with the accompanying drawing, is a specification, like characters on the drawing representing like parts.

This invention relates to improvements in warp tension mechanisms for looms, and the principal object of the invention is to provide means for automatically locking the warp beam against rotation or let-off when the loom is stopped. In looms particularly of the types which are provided with a friction let-off a uniform tension is maintained upon the warp during the operation of the loom, but when the loom is stopped for any considerable length of time the strain upon the warps overcomes the friction so that the warp beam is gradually rotated and the warp let off. This diminishes the predetermined tension upon the warp so that when the loom is again started a thin place is woven in the goods before the predetermined tension upon the warp is resumed.

One of the objects of the present invention, therefore, is to provide means which will prevent the rotation of the warp beam during the stoppage of the loom.

A further object of the invention is to provide a mechanism which will automatically lock the warp beam against rotation when the loom is stopped, but which will not release the locking mechanism until the loom is again started, so that there will be no slackening of the tension upon the warp by reason of premature unlocking of the tension applying mechanism.

It is sometimes desirable to adjust the tension upon the warp while the loom is stopped. A further object of the invention, therefore, is to provide manually operable means for rotating the warp beam notwithstanding the operation of the locking mechanism.

Other objects and features of the invention will more fully appear from the following description and the accompanying drawings and will be pointed out in the annexed claims.

In the drawings:

Fig. 1 is a side elevation of a loom having 55 my invention applied thereto,

Fig. 2 is a detail view of the locking mechanism as applied to the shaft of a hand wheel which is manually operable to rotate the warp beam,

Fig. 3 is a detail sectional view showing the manner in which the ratchet, which comprises a part of the locking mechanism, is frictionally secured on the shaft of the hand wheel, and,

Fig. 4 is a detail view illustrating the clutch shifting mechanism for starting and stopping the loom through which the locking mechanism for the tension applying means is actuated.

The invention is illustrated herein as applied to the well known "Northrop" type of loom, but it will be understood that it may be embodied in other types of looms within the spirit and scope of the claims herein.

The loom illustrated in the accompanying drawings comprises side frames 1 which support the usual mechanism of the loom including bearings for the various shafts thereof. In the present instance a supplemental frame is provided which comprises standards 2, 3 which may rest at their lower ends upon the floor and at their upper ends carry a transverse member or beam 4 which is connected to the loom side at one end, (the left), by a suitable strut or beam, and at the other end by a spacing rod 5 preferably having reduced end portions which are rigidly connected respectively to the cross beam 4 and the loom side 1. The spacing rod 5 also serves to support a slideable member of the clutch actuating mechanism as will herein-after more fully appear.

The driving shaft 6 of the loom is journaled in suitable bearings in the loom side 95 and in a bearing 7 which is mounted upon the transverse beam 4 of the supplemental frame. Power is applied to the driving shaft 6 through a pulley 8 which is rotatably and slidably mounted on the driving shaft 6, 100 said pulley being provided with a clutch member which is adapted to engage a co-operating clutch member fixedly secured to said main driving shaft.

Any suitable means may be utilized for 105 shifting the pulley to cause engagement and

disengagement of the clutch members. The preferred mechanism illustrated herein is of the "easy shipper" type, such as is illustrated in my prior Patent No. 904,450 granted 5 ed November 17, 1908, and the patent to Ambler No. 867,934 granted October 8, 1907, which comprises a lever 9 having a forked end 10 provided with slots to receive pins 10 projecting diametrically oppositely from a sleeve which engages a groove upon the pulley hub.

The lever 9 is provided with a hub 11 which is fulcrumed on a vertical pin carried by a bracket 12 mounted upon the transverse member 4 of the supplemental frame. The opposite end of the lever 9 is provided with a slot which receives a pin 13 projecting upwardly from a skeleton sleeve or frame 14 which is slidably mounted upon the tie 15 rod 5 which connects the supplemental frame to the loom side.

A spring 15, abutting against the end of the skeleton sleeve 14, serves normally to force the same toward the loom side, thus 25 rocking the lever 9 in a direction to shift the clutch members out of engagement. The clutch shifting lever is moved in the opposite direction through a toggle comprising members 16 and 17 pivotally connected respectively to a boss 18 upon the skeleton sleeve and to a bracket 19 carried by the loom side, the pivotal connection 20 of the toggle being connected to the forked end 21 of a link 22 which is connected at its opposite end to 30 an arm 23 of the hand shipper lever 24.

The construction thus described is usual and forms no part of my invention except in so far as this starting and stopping mechanism is employed to actuate the mechanism 40 for locking the tension applying means when the loom is stopped and for releasing said locking means when, or preferably after, the loom is started.

The warp beam 25 of the loom is provided 45 with a gear 26 which engages a pinion 27 which is fixedly secured upon the shaft 28 of a brake drum 29. The periphery of the brake drum is engaged by a brake strap 30 which is anchored at one end to a bracket 50 or cross girder 31 secured to the loom side and is attached at its free end to an arm 32 of a bell crank lever which is pivoted upon a shaft 33 upon the loom side, the opposite 55 end of said bell crank lever being connected by a link 34 to one arm 35 of another bell crank lever, the opposite arm 36 of which is connected to a rod 37 extending to the front end of the loom and provided with usual means for adjusting the tension upon the 60 brake strap 30, whereby the amount of tension applied to the warp may be adjusted.

As illustrated herein the warp 38 runs from the warp beam over guide rolls 39 and 40 and a whip roll 41 through harnesses, not 65 shown, and across the lay 42, and the cloth

passes around the sand roll 43 and the positively driven take-up roll 44 to the usual cloth roll, not shown, the construction thus described being of a usual type.

It is desirable that means shall be provided for rotating the warp beam after the tension upon the brake strap has been adjusted for the predetermined working conditions of the loom. In the present invention this is accomplished through a hand wheel 75 45, located above the lay in convenient reach of the operator, upon the end of a rod 46 which extends downwardly and rearwardly and is provided with a beveled pinion 47 which engages a beveled gear 48 which is 80 secured to the brake drum 29 or to the brake drum shaft 28.

It is found that during the stoppage of a loom which is provided with a frictional let-off, the strain upon the warp will cause 85 a rotation of the warp beam notwithstanding the resistance of the braking mechanism therefor, and that when the operation of the loom is resumed a thin place in the cloth is produced. The present invention contemplates broadly the provision of means for locking the warp beam against rotation during the stoppage of the loom. A preferred mechanism for accomplishing this purpose, 90 which is disclosed herein, comprises a locking device which is rendered effective upon actuation of the stop mechanism and which preferably is released by the same mechanism when the latter is actuated to start the loom.

In the preferred embodiment of the invention disclosed herein the locking mechanism comprises a ratchet carried by the hand wheel rod 46 which is engaged by a pawl which is controlled by the movement of the 105 clutch actuating lever 9. The ratchet 49 of this locking mechanism preferably is rotatably mounted upon a sleeve 50 having a hub 51 which is fixedly secured by a pin 52 to the hand wheel rod 46, a washer 53 being interposed between the ratchet 49 and the hub 51. The opposite side of the ratchet 49 is engaged by a washer 54 which is clamped upon it by a collar 55 engaged by suitable nuts 56 and 57 having screw threaded engagement with the end of the sleeve 50, (see Figure 3). By reason of this construction the ratchet 49 can be frictionally clamped upon the rod 46 in such a manner that the hand wheel may be rotated manually to 110 adjust the warp beam even though the latter is locked against rotation by the strain of the warp, it being only necessary to supply sufficient power to the hand wheel to overcome the friction in the connection between the ratchet 49 and the members which secure it upon the hand wheel rod.

Any suitable mechanism, either manually operated or automatically operated, may be employed to co-operate with the ratchet 49 to 120 125 130 135 140 145 150 155 160 165 170 175 180

lock the warp beam against rotation. As illustrated herein the co-operating member comprises a pawl 58 which is pivotally mounted upon a stud 59 upon the upper end 5 of a bracket 60 having an offset leg 61 which is secured to the loom side by bolts 62. The pawl 58 is provided with a counterweight 63 which tends to force the pawl into engagement with the ratchet. The pawl, however, 10 is normally withheld from such engagement during the running of the loom by a mechanism which is controlled by the clutch shifting lever 9.

In the present construction the pawl 58 is 15 provided with a downward extension 64 having a slot 65 which is engaged by the offset upper end 66 of a link 67, the lower end of which is connected to the arm 68 of a bell crank lever which is pivotally mounted 20 upon a stud 69 projecting from a downward extension 70 of the bracket 60. The other arm 71 of said bell crank lever extends into the slot in the end portion of the clutch shifting arm 9 which receives the stud 13 25 upon the skeleton sleeve 14.

When in the operation of the machine the shipper 24 is released from operative position and moved rearwardly, as illustrated in Fig. 1, the clutch shifting arm 9 is moved 30 laterally, (to the right), by the spring 15. This movement forces the lower end of the arm 71 laterally, thus raising the arm 68 and link 67 and permitting the counterweight 63 to force the pawl 58 into engagement 35 with the teeth of the ratchet 49. This locking engagement holds the hand wheel rod 46 against rotation and since the beveled pinion 47 is fixedly secured to the hand wheel rod and engages the gear 49 upon the brake 40 drum, the brake drum is likewise locked against rotation. As the gear 27 on the 45 brake drum shaft engages the gear 26 upon the warp beam the warp beam is also locked against rotation and the original tension thereby maintained upon the warp during the stoppage of the loom.

In order to prevent any slackness in the warp when the locking mechanism is released and to insure the maintenance of a 50 uniform tension upon the warp it is desirable that the locking means should remain in locked position until after the mechanism of the loom is started. This is readily accomplished by making the slot 65 of sufficient length to provide a certain amount of lost motion for the end 66 of the link 67 before it effectively engages the pawl to withdraw it from the ratchet 49. It will, therefore, be obvious that when the shipper 60 lever is moved to operative position, and the toggles 16 and 17 straightened, a sufficient movement of the skeleton sleeve 14 may take place to cause the clutch shifting lever 9 to start the loom before the offset end 66 of the 65 rod 67 has engaged the end of the slot 65 so

as to withdraw the pawl 58 from engagement with the ratchet 49. Consequently the locking mechanism is not released until after the loom is started and the take-up roll sufficiently rotated to maintain the pre-determined tension upon the warp. 70

Furthermore, by reason of the capability to rotate the warp beam through the hand wheel 45, notwithstanding the fact that the warp beam is locked against rotation by the 75 strain upon the warp, suitable adjustments in tension may be made by the operator without varying the predetermined tension upon the brake band which controls the tension upon the warp during the operation of 80 the loom.

It will be understood that the embodiment of the invention disclosed herein is of an illustrative character and is not restrictive, that various modifications may be made in 85 construction, and arrangement of parts. It will also be understood that the principles of this invention may be applied to various other types of looms and machines in which it is desirable to lock a frictional let-off 90 mechanism against rotation which might be caused by conditions arising during the stoppage of the loom.

Having thus described my invention, what I claim as new, and desire to secure by Letters Patent, is:

1. In a loom comprising a warp beam and frictional means for applying tension upon the warp, starting and stopping mechanism and means automatically operable thereby 100 upon the stoppage of the loom for locking the tension applying means to prevent yielding of said tension applying means by the action of the warp during the stoppage of the loom.

2. In a loom comprising a warp beam and frictional means for applying tension upon the warp starting and stopping mechanism, means automatically operable thereby upon the stoppage of the loom for locking the 110 tension applying means to prevent yielding of said tension applying means by the action of the warp during the stoppage of the loom and automatically operable to release said locking means after the loom is started 115 whereby the tension upon the warp at all times will be maintained.

3. In a loom comprising a warp beam and frictional means for applying tension upon the warp starting and stopping mechanism, 120 means automatically operable thereby upon the stoppage of the loom for locking the tension applying means to prevent yielding of said tension applying means by the action of the warp during the stoppage of the loom 125 and manually operable means for rotating said warp beam while the tension applying means is locked.

4. In a loom comprising a warp beam and frictional means for applying tension upon 130

- the warp and stop mechanism for arresting the operation of the loom, means automatically operable by said stop mechanism to lock said tension applying means when said 5 stop mechanism is actuated to stop the loom.
5. In a loom comprising a warp beam and frictional means for applying tension upon the warp and stop mechanism for arresting the operation of the loom, means automatically operable by said stop mechanism to lock said tension applying means when said 10 stop mechanism is actuated to stop the loom and to release said locking means after said mechanism is actuated to start the loom.
- 15 6. In a loom comprising a warp beam and frictional means for applying tension upon the warp and clutch shifting means for starting and stopping the loom, means automatically operable by said clutch shifting 20 means, when actuated to stop the loom, to lock said tension applying means.
7. In a loom comprising a warp beam and frictional means for applying tension upon the warp and clutch shifting means for 25 starting and stopping the loom, means automatically operable by said clutch shifting means, when actuated to stop the loom, to lock said tension applying means, and operable, when said clutch shifting means is 30 actuated to start the loom, to release said locking means after the loom is started.
8. In a loom comprising a warp beam provided with a gear and means for applying tension to the warp including a brake and a 35 brake drum having a shaft provided with a pinion engaging the gear on said warp beam, starting and stopping mechanism and means automatically operable thereby upon stoppage of the loom for locking said brake 40 drum against rotation.
9. In a loom comprising a warp beam provided with a gear and means for applying tension to the warp including a brake and a brake drum having a shaft provided with a 45 pinion engaging the gear on said warp beam, starting and stopping mechanism, means automatically operable thereby upon stoppage of the loom for locking said brake drum against rotation, and manually operable 50 means for rotating said warp beam notwithstanding the locking of said tension applying means.
- 55 10. In a loom comprising a warp beam provided with a gear and means for applying tension to the warp including a brake and
- a brake drum having a shaft provided with gears including a pinion engaging the gear on said warp beam, a hand wheel having a shaft provided with a pinion engaging a gear on said brake drum shaft, a ratchet on 60 said hand wheel shaft, a pawl tending to engage said ratchet, but normally held out of engagement therewith, starting and stopping mechanism and means operable thereby upon the stoppage of the loom for causing 65 said pawl to engage said ratchet and thereby lock the tension applying mechanism.
11. In a loom comprising a warp beam provided with a gear and means for applying tension to the warp including a brake 70 and a brake drum having a shaft provided with gears and including a pinion engaging the gear on said warp beam, a hand wheel having a shaft provided with a pinion engaging a gear on said brake drum shaft, a 75 ratchet on said hand wheel shaft, adjustable frictional means for securing said ratchet to said hand wheel shaft, a pawl tending to engage said ratchet, but normally held out of engagement therewith, clutch mechanism for 80 stopping and starting the loom and means operable by the actuation of said clutch mechanism to start the loom to permit said pawl to engage said ratchet and thereby lock the tension applying means. 85
12. In a loom comprising a warp beam provided with a gear and means for applying tension to the warp including a brake and a brake drum having a shaft provided with 90 gears and including a pinion engaging the gear on said warp beam, a hand wheel having a shaft provided with a pinion engaging a gear on said brake drum shaft, a ratchet on 95 said hand wheel shaft, adjustable frictional means for securing said ratchet to said hand wheel shaft, a pawl tending to engage said ratchet, but normally held out of engagement therewith, clutch mechanism for stopping and starting the loom, means operable by the actuation of said clutch mechanism to start the loom to permit said pawl to 100 engage said ratchet and thereby lock the tension applying means and operable by the movement of said clutch mechanism in a direction to start the loom to release said locking means. 105
- In testimony whereof, I have signed my name to this specification.

ALONZO E. RHOADES.
